Primary Examiner — Cynthia Ramirez*(74) Attorney, Agent, or Firm* — Oyen Wiggs Green & Mutala LLP(57) **CLAIM**

The ornamental design for a modular pallet, as shown and described.

DESCRIPTION

FIG. 1 is a top isometric view of a modular pallet showing a first embodiment of the new design;

FIG. 2 is a bottom isometric view thereof;

FIG. 3 is a top plan view thereof;

FIG. 4 is a bottom plan view thereof;

FIG. 5 is a first side elevational view thereof;

FIG. 6 is a second side elevational view thereof;

FIG. 7 is a first end elevational view thereof;

FIG. 8 is a second end elevational view thereof;

FIG. 9 is a top isometric view of a modular pallet showing a second embodiment of the new design;

FIG. 10 is a bottom isometric view thereof;

FIG. 11 is a top plan view thereof;

FIG. 12 is a bottom plan view thereof;

FIG. 13 is a first side elevational view thereof;

FIG. 14 is a second side elevational view thereof;

FIG. 15 is a first end elevational view thereof; and,

FIG. 16 is a second end elevational view thereof.

The broken lines in the figures show portions of the modular pallet, which form no part of the claimed design.
